CLAIM

The ornamental design for a radiopharmaceutical synthesis device, as shown and described.

DESCRIPTION

3. Radiopharmaceutical Synthesis Device

FIG. 3.1 is a perspective view of a radiopharmaceutical synthesis device according to the present design;

FIG. 3.2 is a front view thereof;

FIG. 3.3 is a rear view thereof;

FIG. 3.4 is a left side view thereof;
FIG. 3.5 is a right side view thereof;
FIG. 3.6 is a top view thereof; and
FIG. 3.7 is a bottom view thereof.
